UNITED STATES PATENT OFFICE.

AMBROSE KOWASTCH, OF NEW YORK, N. Y.

METHOD OF PRODUCING BLASTING CHARGES IN WHICH LIQUID AIR IS USED.

1,219,645.

Specification of Letters Patent. Patented Mar. 20, 1917.

Application filed November 29, 1913. Serial No. 803,835.

To all whom it may concern:

Be it known that I, AMBROSE KOWASTCH, a subject of the King of Prussia and German Emperor, of 522 East One Hundred and Fifty-ninth street, New York, State of New York, United States of America, mining-engineer, have invented certain new and useful Improvements in the Method of Producing Blasting Charges in which Liquid Air is Used, of which the following is a specification:

My invention relates to improvements in the method of producing blasting charges and to devices for carrying out this method.

It is known in the art to use liquid air or other liquefied gases for producing blasting charges. However, the known processes need being improved in order to avoid certain difficulties which arise in trying to make said method fit for practical purposes.

Now, the process forming the object of the present invention intends to thoroughly obviate the drawbacks and difficulties above referred to.

According to an old process it has been attempted to use for blasting purposes cartridges which were prepared by immersing a material containing carbon (that is a carbon carrier) into an open can or receptacle filled with liquid air. This known method, however, has very considerable disadvantages, the most important of which is firstly the danger involved in the manufacture of cartridges in open pits, and secondly the fact that it was impossible after the cartridge had been introduced into the bore hole in the ordinary manner to provide for a proper closing or tamping of the bore hole, as the gases or vapors escaping from the cartridge ejected any ordinary closure.

These drawbacks are obviated by the present invention according to which the cartridges are prepared outside the bore hole while being protected against fire and so secured are introduced into the bore hole, a venting passage or port being provided in the closure or tamping device through which the vapors are allowed to escape, or the tube for introducing the blasting charge serves to this purpose, or, after having been pulled out, said tube leaves back a suitable opening for escape of said gases.

For producing the blasting charge according to the present method suitable devices and one or several vessels or containers filled with liquid air are used, said vessels or con-

ainers being well insulated and provided with safety valves.

The accompanying drawings illustrate means for carrying out the method according to the present invention.

Figure 1 is a section through a container filled with liquid air and a cartridge immersed therein,

Fig. 2 shows the cartridge containing the blasting charge in its position in the bore hole,

Fig. 3 shows a charging reservoir in side view,

Figs. 4 and 5 show the apparatus in its position of rest near the bore hole and in the discharge position, and Fig. 6 illustrates an arrangement for simultaneously charging several bore holes.

In order to prepare the cartridge in front of the bore hole according to the present method, whereafter the cartridge is introduced into the bore hole, the following apparatus may be used:

For preparing the blasting charge, one or more reservoirs 1 which are well insulated and provided with safety valves are filled with liquid air. The opening of each reservoir is provided with a sheet metal extension 2 as security against fire, a further tube 3 for protecting the cartridge against fire being arranged inside the extension 2. This tube 3 is taken out together with the charged cartridge 4, the latter being first brought into the position 5 shown in dotted lines and then carried together with the protective tube 3 to the bore hole. 6 is a ventilating tube which grips and firmly holds the cartridge. In this tube 6 a tube, rod or the like may be introduced for ejecting the cartridge. A disk 7 arranged upon the tube 6 serves for centrally guiding the cartridge. For the easy manipulation of the tube 3 and the cartridge 4 a handle 8 may be provided. For the automatic opening and closing of the reservoir or container, there is provided a flap valve 10 which is acted upon by a counterweight 9. When the cartridge is introduced into the liquid air container it presses the flap valve 10 downwardly, whereby the vessel is automatically opened. When the cartridge 4 is removed, the opening is automatically closed by the flap valve 10 under the action of the counterweight 9.

The upper openings are opened and closed by means of flaps or slides 12. Fig. 2 shows the arrangement within the

bore hole of a blasting charge. In front of the cartridge 13 there is arranged the tamping material or closure 14, which may be tamping flour, gravel or the like, said tamping material or closure 14 surrounding the tube 13', which serves for leading away the products of vaporization from the cartridge. The tube 13' serves also for holding the cartridge and for introducing liquid air into the cartridge. 15 is a disk surrounding the tube 13', said disk serving as a guide for centering the tube 13', as an obturator for the tamping and also to facilitate the beating down of the tamping. 16 is a tube intended for facilitating the holding of the cartridge. Said tube 16 can be removed before the explosion of the cartridge. Instead of the pipe 13' a needle passed through the tamping closure may be used which maintains an opening in the tamping. After the tamping has been completed, the needle may be pulled out, whereby a passage is left in the tamping which serves the same purpose as the pipe 13', that is, leads away the gases or vapors produced in the cartridge. The tamping material might also be made permeable or untight for enabling the escape of the gases or vapors evolving from the cartridge taking place at the permeable or untight portions of the tamping.

Further, my invention relates to means by which any workman might be enabled to fill the bore hole and the cartridges with liquid air. For this purpose there are suspended close to the bore hole one or more reservoirs containing liquid air and communicating with the interior of the bore hole. These reservoirs may be easily fixed in the position of rest or in the discharge position and are adapted to be easily exchanged. For this purpose the reservoir containing liquid air is provided with an easily detachable holding device which is adjustable and fixable. The reservoir 18, according to Fig. 3, is made of suitable material and is suitably insulated. The narrow neck 19 is provided with a top flange having a recess, while the cover 21 is provided with a projection 20 exactly fitting into said recess. In this manner a very effective closure is obtained. The cover is pressed against the top flange by means of a screw 23 mounted in a yoke shaped member 22. The reservoir may be either cylindrical or spherical or of any other suitable shape. When the reservoir is inclined the liquid air is discharged through the pipe 24. To this pipe is secured an extension pipe 25 by means of a screw nut 26. Into a casing 27 of the extension pipe 25 is arranged a locking disk provided with a locking pawl, clamping screw, bent brake or similar device, which enables the reservoir 18 to be fixed in any desired angular position. The pipe 24 is secured to the reservoir and arranged in such

a manner as to facilitate the manipulation and the fixing of the reservoir 18 in any desired position by means of the locking disk or other device. If necessary a further tubular extension may be fixed to the pipe 24 for instance for the purpose of charging, from the side, bore holes which are very difficult of access. The plug 28 which is inserted into the bore hole is made conical so as to fit bore holes of various diameters. The extension pipe 29 of the pipe 25 leaves an escape passage on being withdrawn. By tilting over the reservoir the liquid air is brought into contact with the metal plates of the closure whereby the vaporization is increased, so that the pressure in the reservoir is sufficiently raised to force the liquefied gases from the cartridge into the bore hole. The pressure might be also raised by admitting the outer air into the liquid air container.

If several bore holes are to be dealt with at the same time several tubes 30 might be branched off from a distribution pipe 32 supplied by the reservoir 31, as shown in Fig. 6.

On preparing a blasting charge by the aid of liquid air it was generally supposed up to the present that the blasting mass was to be composed according to the principles admitted for producing the actual explosives. If liquid air, or, for example liquefied oxygen, is employed, a too high blasting temperature is developed, when no special preventive means are provided for, said temperature being so high that fire damp and coal dust might be ignited by a blown out shot. In order to avoid this drawback it has been found of advantage to add to the components of the explosive in the cartridge a certain quantity of water. Now, while the old safety explosives lose their blasting properties on containing a percentage of water as low as 5%, safety explosives if liquid air is used still explode perfectly well even when the same contain 20% of water and more, without igniting fire damp or coal dust.

It is important not to add directly water to the carbon carrier, but to bind the water to infusorial earth or analogous absorbing material and further to mix said material with the remaining components of the cartridge. Of course, in safety explosives also substances extinguishing the flame are to be added, as for example common salt, sodium bicarbonate, etc. The action of the water is based upon its property to absorb a relatively great quantity of heat; first, the water freezes in consequence of the coldness of the added liquid air whereby 80 calories or units of heat are bound for each kilogram of water; further, the produced ice is still cooled to a greater degree. Now, when the explosion takes place, as owing to the ini-

mate mixture of the components the whole mass is penetrated by substances saturated with water, the produced ice which is cooled up to a high degree is first liquefied by the 5 blasting flame and is then vaporized. In consequence thereof such a lowering of the temperature of the shot flame is produced that an igniting of fire damp or of coal dust is rendered impossible. The security of the 10 shot flame might be further enhanced by adding carbon carriers, which contain a certain quantity of water, for example solutions of sugar or meal or pulverized curcuma and the like soaked with water.

15 To the preceding modes of execution of the process the following igniting process is adapted.

The ordinary igniters or primers are prepared so as to be completely ready for use, 20 that is they still contain blasting chemicals, which are brought to explosion by means of an incandescent wire or a spark, and by transmission of the heat produced in this way or by pressure the explosion of the remainder, that is, of the blasting charge 25 proper, is afforded.

It has already been tried to obtain, by introducing suitable gases or liquids in little blasting or detonating-caps, the same result 30 as with ordinary detonating caps or primers.

The latter blasting method, however, has not been successful, because the manufacture of such detonating caps or primers was complicated and the same were not reliable in 35 their action.

Having thus described my invention, what I claim and desire to secure by Letters Patent of the United States is:—

1. A method of producing blasting 40 charges with the use of liquid air and other liquefied gases, in which the cartridge is prepared outside of the bore hole, consisting in providing means for enabling the evolving gases to escape from the cartridge and means 45 for securing the cartridge against fire, and introducing the cartridge together with said means for securing the cartridge against fire into the bore hole.

2. A method of producing blasting 50 charges with the use of liquid air and other liquefied gases, in which the cartridge is prepared outside of the bore hole, a tube for introducing the blasting charge and means

for securing the cartridge against fire being provided, consisting in using said tube for 55 introducing the blasting charge also for the escape of the gases evolving from the cartridge, and introducing the cartridge together with said means for securing the cartridge against fire into the bore hole. 60

3. A method of producing blasting charges with the use of liquid air and other liquefied gases, in which the cartridge is prepared outside of the bore hole, which consists in providing the cartridge having a 65 tamping material with a vent pipe extending through the tamping material, and inclosing the cartridge during its manufacture in a protecting cover for the purpose of enabling the blasting charge to be safely inserted into the bore hole.

4. A method of producing blasting charges with the use of liquid air and other liquefied gases in which the cartridge is prepared outside of the bore hole, consisting in 75 providing the tamping material itself with a venting port, and inclosing the cartridge during its manufacture in a protecting cover for the purpose of enabling the blasting charges to be safely inserted into the bore 80 hole.

5. A method of producing blasting charges, consisting in using liquid air and adding to the blasting mass in the cartridge an enhanced quantity of water, in order to 85 afford a low blasting temperature, so as to prevent blowing out shots from igniting fire damp or coal dust.

6. A method of producing blasting 90 charges, consisting in adding to the blasting charge such kinds of carbon carriers, which contain a certain percentage of water, such as a solution of sugar or for example of meal or pulverized curcuma soaked with water.

7. A method of producing blasting 95 charges consisting in adding water to the cartridge and bringing this water to freezing by addition of liquid air in suitable quantities, for the purpose of lowering the temperature of the shot flame.

In testimony whereof I affix my signature in presence of two witnesses.

AMBROSE KOWASTCH.
